UNITED STATES PATENT OFFICE.

EARL H. BRADLEY, OF HIGBEE, MISSOURI.

FOLDING STEP FOR VEHICLES.

1,244,830.

Specification of Letters Patent. Patented Oct. 30, 1917.

Application filed May 15, 1917. Serial No. 168,732.

To all whom it may concern:

Be it known that I, EARL H. BRADLEY, a citizen of the United States, residing at Higbee, in the county of Randolph, State of Missouri, have invented certain new and useful Improvements in Folding Steps for Vehicles; and I do hereby declare the following to be a full, clear, and exact description of the invention, such as will enable others skilled in the art to which it appertains to make and use the same.

This invention is an improvement in vehicle steps and has particular reference to a folding step therefor.

An object of the invention is to provide a folding step of simple and improved construction connected to the lowermost stationary step of a railway car or other vehicle and readily and quickly adjustable to operative and inoperative positions.

The inventive idea involved is capable of receiving a variety of mechanical expressions, one of which, for the purpose of illustrating the invention, is shown in the accompanying drawing, wherein:—

Figure 1 is a side elevation of a folding step in operative position.

Fig. 2 is a similar view showing the step in folded or inoperative position.

Fig. 3 is a front elevation showing the step in operative position.

Fig. 4 is a section on the line 4—4 of Fig. 3.

Referring more particularly to the drawing, the numeral 5 indicates the lowermost stationary step of a railway car of a vehicle having secured transversely to each end thereof a supporting bar 6, the ends of which project slightly beyond the front edge of the step and provided with hinges 7.

Connected to these hinges are the hanger arms 8 which depend in a vertical direction when the folding step is in operative position, said hanger arms being connected intermediate their ends by a brace 9. The lower ends of the hanger arms 8 have pivotally connected thereto the step supporting bars 10 secured to the under side of the folding step 11 by suitable fasteners. Each end of the step 11 has secured thereto one end of a brace 12 preferably made in sec-

tions pivoted at adjacent ends so that the step may be folded, the other end of the brace being secured to the bar 6 in any preferred manner.

Means for adjusting the step 11 to its folded position preferably comprises a flexible element 13 having one end secured to the intermediate portion of the hangers 6 and extending downwardly therefrom to a pulley 14 carried by the adjacent supporting bar 10 and from thence to the forward end of said bar and upwardly to a point where the other end of said flexible element is secured at any convenient place adjacent the step 5. It will thus be seen that by pulling upwardly on the flexible element 13 the folding step 11 will first be swung to a substantially vertical position and in engagement with the hangers 8 and further pull upon said element 13 will swing the hangers 8 about their hinges 7 until the folding step is adjusted to the position shown in Fig. 2. By simply grasping the folding step 11 and pulling outwardly from the same it may be adjusted from its inoperative to the extending or operative position thereof.

What is claimed is:—

The combination with a stationary step, of supporting bars secured thereto, hanger arms pivoted to said supporting bars and depending therefrom, other supporting bars pivoted to the lower ends of said hangers, a folding step carried by the last named bars, a flexible element having one end secured to one of the first named bars, a pulley carried by one of said last named bars and around which said flexible element passes, the intermediate portion of said flexible element extending around the forward longitudinal edge of said foldable step and from thence upwardly to a point adjacent said stationary step whereby a pull upon said flexible element will adjust said folding step and hanger arms to a position above said stationary step.

In testimony whereof, I affix my signature in the presence of two witnesses.

EARL H. BRADLEY.
